(57) **CLAIM**

The ornamental design for a cartridge for extraction of solids
for chromatography analysis, as shown and described.

DESCRIPTION

FIG. 1 is a front view of the cartridge for extraction of solids
for chromatography analysis of the present invention, the
back view being a mirror image thereof;

FIG. 2 is a left side view thereof, the right side view being
a mirror image thereof;

FIG. 3 is a top view thereof;

FIG. 4 is a bottom view thereof;

FIG. 5 is a cross-sectional view taken along lines V—V of
FIG. 1; and,

FIG. 6 is a perspective view thereof.
